Specification for Design.

Patented Oct. 5, 1920.

Application filed July 9, 1920. Serial No. 395,171. Term of patent 14 years.

To all whom it may concern:

Be it known that I, GEORGE C. Wood, a citizen of the United States, and a resident of Boston, in the county of Suffolk and State of Massachusetts, have invented a new, original, and ornamental Design for a Rubber Heel, of which the following is a specification, reference being had to the accompanying drawing, forming part thereof.

The figure is a plan view of a rubber heel, showing my new design.

I claim:

The ornamental design for a rubber heel, as shown.

In witness whereof, I have hereunto set my hand this 19th day of June, 1920.

GEORGE C. WOOD.
